MULTI-PIVOT BOWLING PIN WITH SWITCH

John Rosenberger, Roselle, Ill., assignor to Raymond T. Moloney, Chicago, Ill.; American National Bank and Trust Company of Chicago, executor of said Raymond T. Moloney, deceased

Filed Dec. 30, 1957, Ser. No. 706,056

2 Claims. (Cl. 273—41)

The principal object of the disclosed improvements is the provision of a simple control switch for simulated bowling pins used in coin-controlled games and the like.

The novel control switch means is especially adapted for use with the type of bowling pin employing a compound lever system of the type which affords several degrees of movement in the reactions of the pin when struck by a ball. In this regard, a specific feature of the switch means is the provision of a switch-actuating lever carried as an independently movable part of the compound lever system (so as to move bodily with the latter) and capable of actuating a relatively stationary pin-control switch through motion imparted thereto by a simulated bowling pin which is also supported for limited independent primary motion by the lever system, and which is also bodily movable (i.e. to a "struck" or retracted condition) with and by said lever system, in a secondary type of movement.

Another feature resides in the provision of a simple control circuit for any pin unit by which the pin may be released under two different conditions, i.e. when the ball actually strikes the pin, or when the ball strikes some other switch, such as an "alley" switch, or strikes some other pin and actuates the corresponding pin switch which may be connected in a releasing circuit for the first-mentioned pin, as will more fully appear hereinafter.

Additional objects and aspects of novelty and utility will appear as the following description proceeds in view of the annexed drawing, in which:

Fig. 1 is a vertical section of a complete pin unit with parts shown in elevation and the pin shown in pendant playing condition;

Fig. 2 is an operational modification of the showing of Fig. 1 with the pin and lever system in different conditions of operation; and including a schematic circuit diagram;

Fig. 3 is a top view of the pin unit, to reduced scale.

The particular simulated bowling pin structure depicted in Fig. 1 forms the subject matter of co-pending application Serial No. 689,396, filed October 10, 1957, and Letters Patent referred to therein (Nos. 2,722,422 and 2,800,650 to Charles T. Breitenstein) and accordingly only the components and aspects thereof which are essential to an understanding of the present disclosures will be described in detail.

Referring to Fig. 2, the pin body 10 is a half-shell of plastic, synthetic rubber, or the like, having a metal bracket 11 attached interiorly thereof near the neck of the pin by means of screws 12 threaded into bosses molded in the body.

At its lower end, the bracket 11 is forked, only one side 11A of this formation being seen in the two sectionalized views, the forked portions defining a trunnion or yoke the opposite arms of which support a pivot pin 13, which in turn pivotally supports the lower end of a channel-like lever member 14 having a pivot pin 15 near its mid region and another pivot pin 16 at its top.

A torsion spring 16 is carried on the bracket pin 13 and has one end 16A hooked onto the median pivot pin 15, and its remaining end 16B bearing against the inside of the bracket 11 to urge the pin body into a firm, but yieldably upright position when the lever system is erected or extended, as in Fig. 1. Thus, the pin is individually pivotable about pin 13 as represented by the curved arrow P₁ when the lower regions of the body are struck by a ball moving in the direction of the fletched arrow B.

The pin is supported from its own individual base plate 11 by means of a long lever 20 pivotally connected at 21 to a lug on said plate and also pivotally connected at its lower end to the median pivot pin 15 in the lowermost lever arm or pin lever.

Another one of the compound levers 24, which may be designated here as the dog-leg or control lever, is pivotally attached at its lower end to the pivot pin 17 on the lower lever 14 while the upper portion of this control lever is pivotally mounted on the base plate by means of a pivot pin 25 seating in spaced upset flanges 25X on said plate.

A large traction spring 26 (Fig. 3) hooks on to an extended pin 27 staked into the dog-leg lever, and the opposite end of said spring is anchored to a lug 28 on the base plate, with the result that there is a steady pull on the dog-leg or control lever tending to turn the same clockwise, so that when this lever is free to move, it will fold the entire compound lever system upwardly into the dotted-line position shown in Fig. 2. The purpose of this complex pin motion is to permit the use of a much larger pin in a confined space, the pin being turned and elevated simultaneously.

The position of the pin shown in Fig. 1 is the pendant or playing position, in which it is maintained against the retractive effort of the spring by means of an electromagnetic latch armature 30 normally and automatically engaging into a latch notch 29 on the end of the dog-leg. When the coil 31 is energized, the lever is free and spring 26 acts to retract the pin.

Resetting of the pin is effected by motor-driven reset means (not shown) connecting with individual reset links 34 for each pin unit.

The structure described thus far is also disclosed in the aforesaid copending application, the novelty claimed in the present disclosure relating only to certain control switch means now to be described.

In order to approach as closely as possible to realistic pin action in simulated bowling games using pins which are not wholly free in the sense of real pins but which 50 of necessity are largely "captive" and therefore incapable of certain normal movements (e.g. sidewise), the disclosed pin is provided (among other things) with an individual freedom of movement about the pin-pivot 13.

Thus, if a ball moving in the direction of arrow B strikes the lower end of the pin only a light glancing blow, without also passing over and operating a score switch 35 in the alley floor or some analogous score-switch means which would cause the main trip-out or latch coil means 30—31 to release the pin for scoring 60 retraction, the pin itself would nevertheless yield and permit the ball to pass freely, and spring means 16 would restore the pin to upright position.

In those prior games employing score switches like the alley switch 35 (one under each pin) the inertia of 65 the compound lever system causes a slight but perceptible delay in reaction of the pin to the hit, with a consequent detraction from realistic effects, and it has been in part the important objective of the individual pin pivot means 13, 16 to augment the sensitivity of the pin to overcome 70 that condition as well as to permit the use of striking balls as distinguished from pucks or small balls which

heretofore have passed wholly beneath the pin and engaged only the appertaining score switches.

Thus, in accordance with the additionally compounded lever system, the pin will react visibly at once to a blow, whether slight or hard, and this reaction may be only at pivot 13 (P_1), or additionally at pivots 15, 16 (P_2, P_3); and occasionally, with certain kinds of ball-actuated switches (not shown, but of which 35 may be regarded as exemplary) the reaction may not include any motion relative to pivot 13, as where the ball hits another pin switch and scores a "strike" causing an automatic retraction of all pins at once.

To the end of still further enhancing pin action, the present improvements provide a leaf-spring control switch 40 mounted on the base plate with one of its contact leaves 41 disposed over a cut-out 18X therein where it can be engaged by a roller 42 on the jutting edge of a smaller dog-leg switch lever 43 pivoted on cross pin 44 on the larger dog-leg lever, it being understood that the latter, like the lower lever 14, consists of two spaced-apart, rigidly-joined, identical stampings, whereas the main suspending lever 20 is preferably only a single flat stamping.

The switch lever 43 is disposed between the two dog-leg stampings, and is seen in elevation since only one of these stampings is seen in the sectional view of the drawings.

The displacement of the switch lever 43 is limited by a stop pin 45 also seated across the two spaced stampings of the large dog-leg lever 24, there being an oversized hole 43H in the switch lever through which said stop pin passes. Thus lever 43 can move back and forth only a small distance determined by the size of the hole 43H.

At its lower end, the switch-actuating lever 43 has a dog-leg offset 43X which serves two purposes, namely, as a counter-balance to minimize the effect of the mass of this lever on the relatively weak switch spring leaf 41, and secondly to dispose a portion of this lever closely in juxtaposition with a metal striker piece 9 carried on the pin-head bracket 11, in such manner that when the pin is normally pendant, in "playing" or "set" position, striker plate 9 will bear against the dog leg or offset 43X to pivot this switch lever counterclockwise and open switch contact 41 away from its companion normal contact, in other words to actuate the switch in one of its operative conditions or senses to an open condition.

Should the pin be struck and move only slightly at 13 in motion P_1 , lever 43 will be moved clockwise by leaf 41, causing switch 40 to be actuated in its second sense or in this instance its closed condition.

In accordance with prior disclosures (e.g. Serial No. 689,396 and Patent No. 2,800,650 to Charles T. Breitenstein) such pin units have included a leaf-spring supervisory switch 50 like switch 40, positioned, as in the top view of Fig. 3, to be engaged by the extended pin 25 to which the main traction spring 26 is attached, in such manner that when the pin is latched in playing position, as in Fig. 1, the supervisory switch 50 will be closed, as indicated in the schematic showing of Fig. 2, in which there is shown an explanatory operating circuit for control of the individual pin.

In Fig. 2, the bowling pin 10 is shown started, and the pin switch 40 is closed, as also is the supervisory switch 50, these two switches being connected in a series circuit respectively from ground or common G through

switch 50, coil 31, via conductor 51 to one terminal of power source (e.g. battery) 52, to complete the circuit via conductor 53 through the pin switch 40 to return to the return circuit G.

Thus, when pin switch 40 closes, as aforesaid, latch coil 31 will be energized to free the retracting lever 24, since the supervisory switch 50 is also closed at this time; but when the pin and lever system is fully retracted (as in dotted lines, Fig. 2) the extended pin 25 (Fig. 3) on 10 the lever 24 will open switch 50 and de-energize coil 31, since power will be no longer needed for this unit until the pin is reset.

It will be understood that the foregoing pin action occurred solely as a result of striking the pin body 10 itself, as distinguished from the actuation of some disjoined switch means such as the ball-operated switch 35.

However, it will be apparent that the novel pin switch means may be used concomitantly in conjunction with other control switches, such for example as the alley 20 switch means 35, which may be connected in shunt with the pin switch 40 so that either the switch 35 or switch 40 may trip out the pin, and alley switches like 35 may be those associated with the same bowling pin, the pin switch 40 with which they are shunted, or with a different pin.

I claim:

1. In a simulated bowling pin of the compound lever type including a pin body and driven-spring-urged lever means connecting therewith and operable to raise and 30 lower the pin body from pendant to retracted position, said pin being also pivotable about a horizontal axis relative to said lever means, a control switch mounted in stationary relation to the pin body and lever means, and a switch operating lever pivotally carried by a part 35 of the lever means with one portion thereof positioned in operative juxtaposition with said switch, and another portion positioned in operative juxtaposition to the head portion of the pin body so as to be moved by the latter in pendant position to actuate the switch into one control condition, and upon movement of the pin body either by said lever means or on its own pivotal axis, to actuate the switch lever and switch means into another control condition.

2. In a simulated bowling pin mechanism, a main 45 lever mechanism, a pin body pivotally attached to said main lever mechanism the latter supporting the pin body for primary swinging movement in a lowered pendant playing position, and being operable to retract the pin body from said lowered position in a secondary movement thereof relative to a ball-rolling surface; a support to which said lever mechanism is attached; a switch carried by said support; and a separate switch-operating member movably carried by said lever mechanism and having a part operatively engageable with said switch 50 for actuation of the latter when the switch-operating member is moved a predetermined amount in a certain direction with said pin body in substantially said pendant playing position, said switch-operating member having another part disposed in the pendant condition of said pin body to be engaged and moved by the latter responsive to the primary type of movement aforesaid.

3. In a simulated bowling pin mechanism, a main lever mechanism, a pin body pivotally attached to said main lever mechanism the latter supporting the pin body for primary swinging movement in a lowered pendant playing position, and being operable to retract the pin body from said lowered position in a secondary movement thereof relative to a ball-rolling surface; a support to which said lever mechanism is attached; a switch carried by said support; and a separate switch-operating member movably carried by said lever mechanism and having a part operatively engageable with said switch 55 for actuation of the latter when the switch-operating member is moved a predetermined amount in a certain direction with said pin body in substantially said pendant playing position, said switch-operating member having another part disposed in the pendant condition of said pin body to be engaged and moved by the latter responsive to the primary type of movement aforesaid.
